US0D1043160S

(12) **United States Design Patent** (10) **Patent No.:** **US D1,043,160 S**
(45) **Date of Patent:** **** Sep. 24, 2024**

(54) **CHAIR**

(71) Applicant: **David John Peterson**, Sarasota, FL (US)

(72) Inventor: **David John Peterson**, Sarasota, FL (US)

(73) Assignee: **David John Peterson**, Sarasota, FL (US)

(**) Term: **15 Years**

(21) Appl. No.: **29/813,912**

(22) Filed: **Nov. 2, 2021**

(51) **LOC (14) Cl.** **06-01**

(52) **U.S. Cl.**

USPC **D6/379**

(57) **CLAIM**

The ornamental design for a chair, as shown and described.

DESCRIPTION

FIG. 1 is a perspective view of the new design for a chair;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines represent portions of the chair that form no part of the claimed design.

1 Claim, 7 Drawing Sheets
